PICTURE BUILDING APPARATUS

James Y. Henry, Greenfield, N. H.

Application July 22, 1938, Serial No. 220,770

3 Claims. (Cl. 35—26)

My invention relates to the art of constructing composite pictures from individual pieces and includes among its objects and advantages the provision of an improved key system and locating means for locating the pieces in proper relation to form a completed picture.

With these and other objects in view, this invention consists in certain novel features of construction, combination and arrangement of parts to be hereinafter more fully described and claimed.

For a complete understanding of my invention, reference is to be had to the following description and accompanying drawings, in which

Figure 1 is an elevational rear view of the picture frame and locating mechanism;

Figure 2 is an elevational view of the front face of the frame illustrating the manner in which the individual pieces may be associated to provide a completed composition;

Figure 3 is a sectional view along the line 3—3 of Figure 2;

Figure 4 is a sectional view taken along the line 4—4 of Figure 2;

Figure 5 is an end view of the same structure illustrating a support therefor;

Figure 6 is an edge view of the support for the picture frame; and

Figure 7 is a plan view of one of the units which is to be combined with other similar units to complete the pictorial composition.

In the embodiment selected to illustrate my invention, I make use of a picture frame 10 which may comprise the usual frame parts 11 and 12. These parts are connected into a unitary structure in the manner of conventional picture frames. The frame parts 11 and 12 are shaped on their rear faces to provide a ledge 13 for supporting a glass 14. To the back face of the frame part 11 I connect cleats 15 which may be made secure by screws 16 threaded into the picture frame. Cleats 15 are arranged in true parallel relation and each is provided with an angular face 17. Each cleat 15 is graduated as at 18 and the graduations are numbered as at 19. The graduations and numbers on one cleat correspond exactly with the graduations and numbers on the other cleat.

A bridge bar 20 has a block 21 attached to each end which block is arranged in right-angular relation to the bridge bar. Blocks 21 have angular faces 22 fitting snugly against the angular faces 17. While the blocks 21 have snug fitting relation with the cleats 15, the blocks are shiftable longitudinally of the cleats. Angular faces 22 are

slidably related to the angular faces 17 but are so inclined as to hold the blocks 21 in connected and sliding relation with the cleats as illustrated in Figure 3. Bridge bar 20 is supported in parallel relation with the glass 14, but the blocks 21 are of sufficient length to hold the bridge bar in spaced relation with the rear face of the picture frame 10.

I provide the bridge bar 20 with graduations 23, which graduations are numbered as at 24. According to Figure 1, the numbering 24 reads from left to right, while the numbering on the cleats 15 reads from top to bottom.

To the upper frame part 12 I fixedly secure a cleat 25. The lower frame part 12 is provided with two blocks 26 each having an angular end 27. A panel 28 is shaped to fit between the cleat 25 and the blocks 26, which panel is provided with a resilient facing 29 which may comprise fabric or other suitable material. The panel 28 includes a dovetail 30 arranged to have connected relation with the angular end 27, to effectively support the panel against relative shifting. While the panel is restrained from relative shifting, it may be lifted outwardly from the frame 10 and in the clear of the blocks 26.

A pair of arms 31 is pivotally connected with screws 32 anchored in the cleat 25. Screws 32 are provided with wing nuts 33 for clamping the arms 31 in fixed relation with the panel 28. Each arm 31 is slotted at 34 for loosely receiving the shaft 35 fixedly connected with a finger 36. In Figure 4 I illustrate the shaft 35 as including a head 37 which, together with the associated finger 36, holds the finger in connected relation with its associated arm 31. The finger 36 may be shifted longitudinally of the slot 34 and may be rotated to different positions about the axis of the shaft 35. Both arms and finger assemblies are identical in construction so that the description of one will apply to both. In Figures 3 and 4, I illustrate a border insert 38 which may lie on the inner margin of the glass 14. This insert may be made up in series of different proportions depending upon the pictorial composition to be constructed in the frame. The insert may comprise cardboard or other suitable material.

In Figure 7 I illustrate one of the many pieces which may make up the set. The composite picture is constructed through the proper selection of pieces and arranging the pieces in proper assembled relation. According to Figure 7, the piece 39 is provided with pictorial illustrations 40 which may be colored in suitable design. In lieu of pictorial illustrations, the pieces may be pro-

vided with fragmentary geometrical outlines. On each face of the piece 39 I provide a key number 41, a line 42 and a dot 43. Both sides of the piece may be provided with pictorial illustrations, so that either side of the piece may be employed depending upon the composite picture to be constructed.

While Figure 7 illustrates one piece only, a set will include a large number of such pieces. In addition, I provide a list which gives the building order of the pieces in accordance with the key numbers, one of which is illustrated at 41 in Figure 7. One method of constructing a composite picture consists in reversing the panel 28, illustrated in Figure 4, to bring the cushion 29 to the exposed position of Figure 1. In Figure 1 I illustrate the piece 39 in place. The proper location of the piece 39 is determined through the medium of the line 42 and the dot 43. Assuming that the key list identifies the piece 39 as having a dash value of 14, the bridge bar 20 is shifted to bring its upper edge into alignment with the graduation or graduations 18 on the cleat 15. In Figure 1 I illustrate the line 14 as being properly related to the bridge bar 20. Assuming that the key list identifies the dot 43 as having a value of 21, the piece 39 is shifted longitudinally of the bridge bar 20 to bring the dot 43 into registration with the graduation 21. The arms 31 have sufficient room underneath the bridge bar 20 to permit shifting of the arms when positioned according to Figure 1. After the piece 39 has been properly positioned, the left hand arm 31 is made secure by tightening the thumb screw 33 associated therewith. Such tightening of the thumb screw causes the fingers 36 to be pressed against the piece 39 for holding it in fixed relation with the cushion panel 28.

Figure 1 illustrates a second piece 44 which includes a key number 45 corresponding to the key number 41 on the piece 39. The dash or line 46 on the piece 44 is of the same value as the line 42 of piece 39. The dot 47 has a value of 45 and is located in registration with the graduation of that number on the bridge bar 20. It will thus be seen that additional pieces may be incorporated in the picture to provide a composite finished picture as illustrated at 48 in Figure 2. As each individual piece is placed in position the arms 31 may be shifted and made secure for holding that piece or a group of pieces in assembled relation.

After the proper number of pieces have been assembled on the panel 28, the bridge bar 20 is removed and the arms 31 are pivoted entirely in the clear of the panel. This should be done carefully so as not to disturb the arrangement of the pieces. The panel is removed carefully from the frame 10 and placed on a support, such as a book, with the edges of the panel projecting beyond the support. The frame is then turned over and properly related to the panel which brings the individual pieces of the picture into pressure relation with the glass. The resilient facing 29 is such as to have effective pressure relation with the individual pieces. The frame 10 and the panel 28 are now grasped and turned over as a unit and placed back upon the support. The panel 28 is removed and reversed to bring the resilient facing 29 into pressure relation with the individual pieces. At this time the arms 31 are pivoted over the panel 28 and pressed thereagainst by tightening the wing nuts 33. By tightening the wing nuts 33, the panel 28 will be effectively pressed against the individual pieces

and the parts will be connected into a firm and unitary structure.

An alternative method in constructing the composite picture consists in positioning the frame 10 with its face down, but with the panel 28 removed. The border 38 is then placed in position after which the individual pieces are placed in their numerical order on the glass 14. The line and dot indicators are related to the graduations 18 and 23 in the manner previously described. After all the pieces have been laid the panel 28 is placed in position with the cushion 29 pressed against the pieces.

In the first method described, the picture is exposed to view as it is being constructed, but in the second method the picture is upside down and not exposed to view until finally completed and made secure. It will thus be seen that I have provided novel means which may be manipulated to secure precise location of the individual pieces. The individual pieces may be assembled into a predetermined pattern and made secure without the aid of pins, glue, etc. The system may be employed to teach children the simple, fundamental rules of picture making. Any child or person can easily create or construct individual pictures from the pieces provided in the set. A constructive picture may be taken apart without damage to the individual pieces, and the pieces can be used over and over again.

In Figure 5, I illustrate the manner in which the frame 10 may be supported in a substantially upright position for display. A prop 50 is provided with a slot 51 shaped to receive the bridge bar 20. For such purposes, the bridge bar 20 is pushed upwardly of the cleats 15 for bringing the blocks 21 into pressure relation with resilient pads 52 connected with the ends of the cleat 25. The blocks 21 will be effectively pinched between the pads 52 and the angular faces 17. With the prop connected with the bridge bar 20, according to Figure 5, the frame 10 is supported at a slight angle to the vertical for display purposes.

I claim:

1. A device of the type described comprising a work support, a series of individual pieces each having a key mark with the pieces adapted to be arranged in a predetermined order to provide a composite pattern, a frame of rectangular contour extending about the perimeter of the work support, a bridge bar extending transversely of the frame with its ends slidably related to the side runs of the frame, said side runs being graduated to determine the location of the bridge bar vertically of the frame and said bridge bar being graduated for cooperating with the key marks on the individual pieces for locating the latter in said predetermined order, arms each having one end pivotally connected with the top run of said frame and adapted to extend underneath said bridge bar, and fingers slidably and pivotally connected with the other ends of said arms to have pressure relation with individual pieces on said work support, said fingers lying underneath said arms with the latter and said fingers so arranged as to be movable for bringing the fingers into pressure relation with localized areas throughout the work support.

2. A device of the type described comprising a work support, a series of individual pieces each having key means and adapted to be arranged in a predetermined order to provide a composite pattern, a frame of rectangular contour extending about the perimeter of the work support, a

bridge bar extending transversely of the frame with its ends slidably related to the side runs of the frame, said side runs being graduated to determine the location of the bridge bar vertically of the frame and said bridge bar being graduated for cooperation with the key means of the individual pieces for locating the latter in said predetermined order, an arm having one end pivotally connected with the top run of said frame and adapted to extend underneath said bridge bar, a finger slidably and pivotally connected with the other end of said arm to have pressure relation with individual pieces on said work support, said finger lying underneath said arm with the finger and the arm so arranged as to be movable for bringing the finger into pressure relation with localized areas throughout the work support.

3. A device of the type described comprising a work support, a series of individual pieces each having a key mark for determining the vertical location of that piece on the work support and a second key mark for determining the hori-

zontal location of the piece, a frame of rectangular contour extending about the perimeter of the work support, a bridge bar extending transversely of the frame with its ends slidably related to the side runs of the frame, said side runs being graduated to determine the location of the bar vertically of the frame in conformity with the key marks on the individual pieces for determining the vertical position thereof, said bridge bar being graduated for cooperation with the other marks of the individual pieces for locating the latter horizontally of the work support, arm means movably connected with the top run of said frame and adapted to extend underneath the bridge bar, and finger means slidably and pivotally connected with said arm means to have pressure relation with individual pieces on said work support, said finger means and said arm means being so constructed and connected for relative movement as to bring the finger means into pressure relation with localized areas throughout the work support.

JAMES Y. HENRY.
